UNITED STATES PATENT OFFICE.

JOHN D. TOMPKINS, OF VALATIE, NEW YORK.

PROCESS OF DRYING AND BLEACHING.

1,037,370.

Specification of Letters Patent. Patented Sept. 3, 1912.

Application filed December 20, 1910. Serial No. 598,312.

To all whom it may concern:

Be it known that I, JOHN D. TOMPKINS, of Valatie, in the county of Columbia and in the State of New York, have invented a 5 certain new and useful Improvement in Processes of Drying and Bleaching, and do hereby declare that the following is a full, clear, and exact description thereof.

My invention comprises a process and an 10 apparatus for drying and bleaching wet materials of all kinds, but more specifically wet paper, which have many advantages not possessed by systems which have been hitherto used for this purpose.

15 The object of my invention is especially to provide a process and an apparatus which will dry and bleach a traveling web of paper continuously by the aid of electricity.

My invention, furthermore, is such that 20 the paper is effectively dried without the aid of a high degree of heat. The paper dried in accordance with my invention is, therefore, dried well below the temperature at which fibers are injured or paper stock 25 chars. As a result, the paper so dried is far stronger than paper which has been dried by systems hitherto used which have invariably involved the application of a high degree of heat.

30 Furthermore, my invention is such that a current of electricity is caused to pass through the body of the traveling web of paper and as a result a considerable quantity of oxygen is formed upon the lower face

35 of a traveling web of paper, thereby resulting in the web of paper being effectively bleached, inasmuch as a considerable percentage of the oxygen so produced passes through a body of the web of paper before 40 it escapes.

I have shown one type of apparatus adapted to be used in connection with my process in the following drawings, in which—

45 Figure 1 represents a vertical section of my apparatus, and Fig. 2 is a detailed view of a portion of one end of the metal belts used in my apparatus.

In the drawings, 1 is a housing closed at 50 the bottom and having front and rear openings 2 and 3 to receive and discharge a traveling web of paper 4. The top of the housing 1 is provided with a funnel 5 having a discharge pipe 6, leading to an exhaust apparatus of any desired kind. At the inlet opening, there is provided a small

endless belt 7 supported upon rollers 8 for feeding the web of paper 4 into the apparatus. Within the housing 1 there are provided upper and lower foraminous metal 60 belts, 9 and 10, which are driven, respectively, by power-driven rollers 11 and 12. Between the rollers 12 there are provided an additional pair of rollers 13 for supporting the belt 10 between the rollers 12. 65 A pair of idlers 14 and 15 are provided for supporting the metal belts between the driving rollers at the points where the belts are not in contact with the traveling web of paper 4. A source of electric energy 16 is 70 connected at its positive pole by means of a wire 17 to a rheostat 18 and a wire 19 to a series of brushes 20 situated upon the under-face of the metal belt 10 at the portion where it supports the traveling web of 75 paper 4. A wire 21 connects the negative pole and the source of electric energy 16 with a similar series of brushes 22 located in a similar manner adjacent the surface of the upper belt 9 opposite the portion thereof 80 which supports the traveling web of paper 4. At the discharge aperture 3 there is provided a guide or doctor 23 operating against the face of the belt 10 to prevent the web of paper from being carried by said belt 85 around the left-hand roller 12 and a roller 24 is provided at the end of the guide or doctor 23 to reduce the friction of the traveling web of paper while it is being delivered from the apparatus. 90

In the operation of said apparatus, the wet material, preferably a web of wet paper 4 is fed into the opening 2 by means of the endless belt 7 so that it passes between the foraminous metal belts 9 and 10. An electric current, being generated by the source of electricity 16, the current which is regulated by the rheostat 18, is passed from the brushes 20 through the metal belts and the interposed web of paper 4 to the brushes 22 100 and back to the source of electricity 16 by means of wire 21. The water which is present in the web of paper 4 is decomposed under the action of the electric current, the oxygen thereof going to the lower belt 10, 105 which is the positive pole, and the hydrogen passing to the upper belt 9, which is the negative pole. The oxygen thus liberated passes in part, at least, through the body of the traveling web of paper and as a consequence, the web of paper is effectively 110 bleached as well as dried. The generation

of nascent oxygen within the body of the web of paper also conduces to the bleaching of the traveling web of paper. The passage of the current of electricity through the materials being treated may be facilitated by using an electrolyte such as sea water or other saline water for wetting them.

While I have described my process and one type of apparatus in which it may be carried out, in detail, I wish it to be understood that many changes may be made therein without departing from the general principles thereof or the spirit of my invention.

15 I claim:

1. The process of drying paper, comprising passing an electric current through a wet body of paper.

2. The process of drying paper, comprising passing an electric current through a wet web of paper.

3. The process of drying paper, comprising passing an electric current through a traveling wet web of paper.

25 4. The process of drying paper, comprising

ing passing an electric current through a traveling wet web of paper containing an electrolyte.

5. The process of drying and bleaching, comprising passing an electric current 30 through a body of wet material, thereby liberating a quantity of oxygen and bleaching said material.

6. The process of drying and bleaching, comprising passing an electric current 35 through a body of wet material thereby drying said material and liberating a quantity of oxygen and bleaching said material.

7. The process of drying and bleaching, comprising passing an electric current 40 through a traveling body of wet material, thereby liberating a quantity of oxygen to bleach said material continuously and drying said material.

In testimony that I claim the foregoing 45 I have hereunto set my hand.

JOHN D. TOMPKINS.
